(57) **CLAIM**

The ornamental design for a glitter pencil with solid color with circular glitters, substantially as shown and described.

DESCRIPTION

FIG. 1 is a front elevational view of a glitter pencil with solid color with circular glitters showing my new design;
FIG. 2 is a side elevational view thereof;
FIG. 3 is a bottom plan view thereof;
FIG. 4 is a top plan view thereof; and,
FIG. 5 is an enlarged fragmentary view of the lower section. The structure depicted by means of broken lines has been shown for illustrative purposes only and forms no part of the claimed design.
